UNITED STATES PATENT OFFICE.

LOUIS H. BRINKMAN, OF GLEN RIDGE, NEW JERSEY.

GOLF STICK.

Original application filed June 24, 1924, Serial No. 721,965. Divided and this application filed October 31, 1925. Serial No. 65,918.

This invention relates to tubular metal shafts for golf sticks.

This application is a division of my application Serial No. 721,965 filed June 24, 1924.

Metal tubes form light, durable and strong shafts for golf clubs but heretofore such shafts have been of tubes of a uniformly tapering diameter and have not had the balance, flexibility at desired points etc., all of which are summed up in the term "feel" of the club.

It is the main object of the present invention to provide tubular metal shafts for golf clubs which shall have the desired "feel".

This is accomplished by suitably varying the taper of the tube diameter and the thickness of the tube wall may be made such, either uniform or varying in thickness at different points, as will contribute to the desired results. The desired "feel" varies with different users but the shaft most often filling the desired requirements is one in which the tube is of reversed taper in tube diameter and having uniform thickness of wall, and such construction is therefore my preferred form.

Other and ancillary objects of the invention will appear hereinafter.

In the accompanying drawings which illustrate the invention—

Fig. 1 is a side elevation of a shaft for a golf club;

Fig. 2 is a view showing the shaft in section;

Fig. 3 is a view of a modified form of golf club showing the shaft in longitudinal section;

Fig. 4 is a view of a modified form of club showing the shaft in longitudinal section; and

Fig. 5 is a view of another modified form of golf club, the shaft being shown in longitudinal section.

In Figs. 1 and 2 the golf shaft shown is of a seamless steel tubing having substantially uniform thickness of wall throughout and having a uniform taper throughout the greater part of its length but having a short section at its end of uniform diameter.

Thus the part 56 is of uniform taper of tube diameter and extends for the greater portion of the length of the shaft to the point 61 and thence to the end is the section 57 of

uniform diameter (the whole shaft being of uniform thickness of wall) adapted to receive the shank 63 of the head 64 of a golf club, the two being secured together in any suitable manner. It will thus be seen that the tube diameter at 61 is the minimum diameter of the shaft.

In Fig. 3 is shown a shaft having a uniform thickness of wall throughout but having a tapered section 78 extending throughout the greater part of its length to a point of minimum diameter 79 and thence tapering oppositely or reversely through a section 80 to a point 81 and thence being of cylindrical section 82 to the end of the shaft.

In Fig. 4 is shown a shaft having a tapered tube of uniform thickness of wall for the section 65 which extends for the greater portion of its length and terminating at the narrowest portion 66 and thence having the section 67 of uniform internal diameter but of increasing external diameter (the tube increasing in thickness) to a point 68 whence the tube shaft extends with uniform thickness of wall and uniform diameter of tube to its end. It is to be observed in connection with the shafts of Figs. 3 and 4 that the points 66 and 79 are those of the least outside diameters of the tube, the shafts being of greater outside diameters upon both sides of those points. This affords a means for decreasing the size of the shaft adjacent the head or whenever desired so as to give suitable flexibility at desired points of the shaft.

In Fig. 5 is shown a shaft the same as that of Fig. 3 except that the wall of the tube is thickened at the waist or portion of least diameter so that while flexibility of the shaft is obtained at that point the club shaft may be strengthened. The shaft as shown in Fig. 5 comprises the portion 110 having a long uniform taper, the wall of the tube being substantially uniform throughout the greater portion of its length. This portion 110 extends to the waist 97 whence the reversely tapered portion 96 extends to the substantially cylindrical portion 99 joined to the head 100 of the club. It will be observed that the wall of the tube is thickened at 97, the wall then tapering in both directions to a thinner wall which obtains throughout the greater portion of the tube. This shaft has advantages as stated.

All of the shafts of Figs. 1 to 5 inclusive, which are seamless, may be formed by the method and apparatus as described in my application Serial No. 721,965 above referred to and of which the present application is a division.

A seamless tube is superior for forming the shafts because the desired characteristics are more readily imparted to it and it retains those characteristics under all conditions of use so that it is more satisfactory, reliable and durable, and especially it is immune from injury by torsional stresses while permitting desired flexibility.

While the invention has been illustrated in what are considered its best applications it may have other embodiments without departing from its spirit and is not therefore limited to the structures shown in the drawings.

What I claim is:

1. A golf club having a head and a shaft comprising a metal tube having reverse tapers and a tube length between one of said tapers and the head end of said shaft, said tube length having a different relationship of succeeding outside diameters from that of the last mentioned taper.

2. A golf club having a head and a shaft comprising a metal tube having a tube length extending from the handle toward the head, said length being of greater diameter at its handle end than at its other end and constituting the greater part of the shaft length, a second tube length between the aforesaid length and said head and having its outside diameter greater at its head end than at its handle end and a third tube length between said second tube length and the head end of

said shaft, said third tube length having a different relationship of succeeding outside diameters from that of the said second tube length.

3. A golf club having a head and a shaft comprising a metal tube having a tube length extending for the greater part of the length of the shaft and being of less outside diameter at its head end than at its handle end, a second tube length adjoining the said tube length and having its handle end of less outside diameter than its head end and a third tube length between the said second tube length and the head end of the shaft, said third tube length having a different relationship of succeeding outside diameters from that of the second tube length, said tube lengths being circumferentially continuous.

4. A golf club having a head and a shaft comprising a metal tube having a waist formed by reversely tapered tube lengths, said tube lengths being circumferentially continuous, and a tube length adjoining one of the aforesaid tube lengths and having a different relationship of succeeding outside diameters from that of its adjacent tapered tube length.

5. A golf club having a head and a shaft comprising a seamless metal tube having a waist formed by reversely tapered tube lengths and a tube extension of substantial length adjoining one of the aforesaid tube lengths and having a different relationship of succeeding outside diameters from that of its adjacent tapered tube length.

In testimony whereof I have signed this specification this 30th day of October, 1925.

LOUIS H. BRINKMAN.
